UNITED STATES PATENT OFFICE.

FRANCIS F. FIELD, OF STAPLETON, NEW YORK.

HELICAL-WIRE BRUSH.

SPECIFICATION forming part of Letters Patent No. 232,636, dated September 28, 1880.

Application filed August 18, 1880. (Model.)

To all whom it may concern:

Be it known that I, FRANCIS F. FIELD, of Stapleton, in the county of Richmond and State of New York, have invented a new and 5 useful Improvement in Helical-Wire Brushes, of which the following is a specification.

My invention relates to that class of wire brushes for cleaning boiler-tubes and for other purposes in which the wire bristles are arranged in helical form upon a central axis by being held at their middle between four longitudinal binding-wires twisted together, said binding-wires being then inserted and secured with their outer ends in a tube threaded for 15 the attachment of a rod, by which latter the brush is operated.

A wire brush of this kind was patented to me in the United States October 10, 1871, by Letters Patent No. 119,752, which shows two 20 single helical rows of wire bristles meeting at their center at right angles to each other.

My present invention is an improvement upon that just referred to, and has for its object to provide a brush of greater compactness 25 and strength, and presenting more points for contact with the surface to be cleaned, thereby conforming more readily to inequalities in the tube and better adapting the brush to hard service.

30 In the accompanying drawings, Figure 1 represents a side view of my improved wire brush. Fig. 2 is an end view of the same, the binding-wires being shown in section. Fig. 3 is a cross-section of the same, showing only 35 two adjacent pairs of single parallel-wire bristles interlacing with the binding-wires.

Similar letters of reference indicate corresponding parts.

A designates the core of binding-wires $a a'$, 40 between which the wire bristles $b b'$ are inserted in rows of alternate layers, at right angles to each other, said rows being caused to assume a helical shape, as in Fig. 1, by twisting together the binding-wires.

45 One end of the core A is inserted and secured in a tube, C, whose end is threaded at c for

attachment to the rod by which the brush is operated.

D is the body of the brush, formed, as aforesaid, of helical rows of wire bristles. 50

In my patent previously referred to the bristles were arranged in single rows, meeting at their centers at right angles to each other, by being inserted parallel with the side of the square formed by the four binding-wires, or, 55 in other words, by being held between four binding-wires, two on each side of the row.

In my present invention (see Figs. 2 and 3) the wire bristles are arranged in double rows or pairs, meeting at opposite sides of their center, at right angles to each other, by being inserted parallel with the diagonals of the square formed by the four binding-wires. 60 Thus the two members $b b$ of one pair, B, are kept separate and parallel with each other by 65 the two diagonally-opposite binding-wires $a a$, and are held between these and the two diagonally-opposite binding-wires $a' a'$, which separate the members $b' b'$ of the adjacent pair B'. So are also the members $b' b'$ of the 70 pair B' held between their separating-wires $a' a'$ and the diagonally-opposite wires $a a$, which separate the members $b b$ of the pair B.

It will be seen that the adjacent wires do not meet at their centers, as in my brush of 75 single rows; but they meet at right angles a little distance from and at laterally-opposite sides of their respective centers.

The members b or b' of each pair B or B' may be inserted singly or in thicknesses of 80 two or more together before inserting the adjacent pair, according to the stiffness desired of the brush.

The steel wires of this double-row brush, by 85 interlacing with the binding-wires in the manner shown, are held more firmly, and the body D of bristles is more compact and presents many more points for contact with the surface to be cleaned than is the case with the single-row brush, thereby also conforming more readily 90 to inequalities or irregularities in the inner surface of the tubes to be cleaned.

Having thus described my invention, I claim as new and desire to secure by Letters Patent—

An improved wire brush in which the adjacent wire bristles are arranged in pairs, B B', of parallel members, the members *b b* of each pair B being separated at their inner edges by two centrally and diagonally opposite binding-wires, *a a*, and held at their outer edges by two centrally and diagonally opposite bind-

ing-wires, *a' a'*, separating the members *b' b'* of the other pair B', the members of one pair meeting those of the adjacent pair at right angles at laterally-opposite sides of their respective centers, substantially as shown and described.

FRANCIS F. FIELD.
